DESIGN FOR A BOTTLE

Charles H. Mekeel, Jr., Reading, Pa.

Application December 6, 1937, Serial No. 73,411

Term of patent 14 years

To all whom it may concern:

Be it known that I, Charles H. Mekeel, Jr., a citizen of the United States, residing at Reading, in the county of Berks and State of Pennsylvania, have invented a new, original, and ornamental Design for Bottles, of which the following is a specification, reference being had to the accompanying drawing, forming part thereof.

Fig. 1 is a perspective elevation of a bottle showing my new design.

Fig. 2 is a corresponding perspective elevation showing the bottle turned upside down.

Fig. 3 is a longitudinal section.

I claim:

The ornamental design for a bottle, as shown.

CHARLES H. MEKEEL, JR.
